UNITED STATES PATENT OFFICE.

ALBERT HARRY SALMON, OF TWICKENHAM PARK, ENGLAND.

SPRING SUPPORT FOR CHAIRS, COUCHES, AND THE LIKE.

Application filed March 31, 1926, Serial No. 98,894, and in Great Britain May 25, 1925.

This invention relates to spring supports for chairs, couches, omnibuses and other vehicle seats and the like and it has for its object to obviate the usual upholstery or 5 internal seat springs.

The present invention consists broadly of a chair, couch or the like composed of two frames, one frame carrying the seat and being mounted upon springs interposed between the two frames whereby the upper frame is free to move in a resilient manner relatively to the other or under-frame.

The preferred spring support according to the present invention consists of or comprises 15 a plurality of conical coiled compression springs arranged so as to constitute the sole supporting means for the upper or seat frame.

In the preferred arrangement the springs 20 are arranged in tandem fashion in two sets on each side of the chair or the like, the rear set consisting of two or more springs and the front set consisting of one or more springs of heavier gauge material or otherwise rendered stiffer than the springs of the rear set.

While conical coiled springs as the support for the upper frame of the article such frame is permitted to give in all directions under the weight of the user whilst completely or almost completely obviating any 30 tendency for the upper frame and consequently the seat to roll owing to the lateral stability imparted by springs of this type.

In order that the invention may be clearly 35 understood two embodiments of the same will now be described by aid of the accompanying drawings in which:—

Fig. 1 is a fragmentary perspective view 40 of an armchair embodying the improvements according to the present invention.

Fig. 2 is a longitudinal vertical section through the same.

Fig. 3 is a plan view.

Fig. 4 is an elevation of the detachable and 45 adjustable back.

Fig. 5 is a fragmentary longitudinal vertical section through a chair having springs of the leaf or laminated type.

The chair illustrated comprises a rectangular frame *a* supported on legs *b* and forming the base for the chair, such frame being hereafter referred to as the base frame. The portion *c* hereafter referred to generally as the body of the chair, is supported, in the 50 example illustrated in Figs. 1 to 4, upon six

conical coiled springs, three of which *d*, *e* and *f* are shown in the drawings. These springs are arranged tandem fashion on opposite sides of the chair with their largest diameter adjacent to the underside of the 60 body of the chair *c*.

In the preferred arrangement which is illustrated, the springs are arranged in two sets, the rear set consisting of the springs *d* and *e* and the front set of the spring *f*. The 65 front springs *f* are composed of heavier gauge material or otherwise rendered stiffer than the springs *d* and *e*.

To render the springs normally invisible the body of the chair is provided all round 70 with a depending skirt *g*.

In the example illustrated in Fig. 5 laminated springs *h* are used in lieu of the conical coiled springs *d* and *e* of the first described example. 75

Alternatively ordinary coil springs may be used.

The conical coiled springs are however preferred as they give in all directions under the weight of the user of the chair whilst completely or almost completely obviating any 80 tendency for the body of the chair to roll owing to the lateral stability imparted by springs of this type.

A chair having a spring support according to this invention does not require any upholstery springs and the seat proper may be composed of a strip of material stretched between the back and front transverse members of the seat frame. 85

What I claim and desire to secure by Letters Patent is:—

A chair comprising an integral under-structure including side rails and end rails, an integral over-structure including seat and back, a set of conical coil springs arranged tandem fashion on each side rail of said under-structure with their smaller ends resting on said side rail and their larger ends supporting said over-structure, the springs supporting the front end of said over-structure being less in number but of heavier gauge than those supporting the rear end of said over-structure and the several springs of the two sets constituting the sole means for limiting relative movement between said two structures in a horizontal sense in all directions. 95

In witness whereof I affix my signature.

ALBERT HARRY SALMON.
